(57) **CLAIM**

The ornamental design for lid for storage container, as shown and described.

DESCRIPTION

FIG. 1 is a top perspective view of a lid for storage container, showing my new design according to a first embodiment.

FIG. 2 is an end view thereof.

FIG. 3 is a front view thereof.

FIG. 4 is a top plan view thereof.

FIG. 5 is a bottom plan view thereof.

FIG. 6 is a top perspective view of a lid for storage container, showing my new design according to a second embodiment.

FIG. 7 is an end view thereof.

FIG. 8 is a front view thereof.

FIG. 9 is a top plan view thereof; and,

FIG. 10 is a bottom plan view thereof.

The broken lines depicting the storage container in FIGS. 1-10 depict environment and form no part of the claim. The broken lines shown on claimed surfaces of the lid in FIGS. 6-10 depict portions of the article and form no part of the claim.

1 Claim, 10 Drawing Sheets
